(57) **CLAIM**

The ornamental design for a door for clothing care machine, as shown and described.

DESCRIPTION

1. Door for clothing care machine

1.1 is a perspective view of a door for clothing care machine, showing our new design;

1.2 is a front elevation view thereof;

1.3 is a rear elevation view thereof;

1.4 is a left-side elevation view thereof;

1.5 is a right-side elevation view thereof;

1.6 is a top plan view thereof;

1.7 is a bottom plan view thereof;

1.8 is a perspective view thereof, shown in a use condition;

1.9 is another perspective view thereof, shown in a use condition; and

1.10 is another perspective view thereof, shown in a use condition.

The broken line shown in figures 1.8 through 1.10 is for the purpose of illustrating environment and forms no part of the claimed design.
